UNITED STATES PATENT OFFICE

109,036

DESIGN FOR A PAPERWEIGHT OR SIMILAR ARTICLE

Sam W. Clutton, Great Falls, Mont.

Application January 5, 1938, Serial No. 74,105

Term of patent 14 years

To all whom it may concern:

Be it known that I, Sam W. Clutton, a citizen of the United States of America, residing at Great Falls, county of Cascade, State of Montana, have invented a new, original, and ornamental Design for a Paper Weight or Similar Article, of which the following is a specification, reference being had to the accompanying drawing, forming part thereof, wherein:

The figure is a perspective view of a paper weight or similar article, showing my new design.

I claim:

The ornamental design for a paperweight or similar article, as shown.

SAM W. CLUTTON.
